UNITED STATES PATENT OFFICE

REUBEN ELI OTTENHEIMER, OF BALTIMORE, MARYLAND

REFRIGERATOR

Application filed August 25, 1927. Serial No. 215,333.

This invention relates to refrigerators and has for its object the provision of means whereby the deposit of frost or dew by condensation of moisture upon the surface of the glass panel in a display refrigerator is prevented, and whereby moisture in the walls, or between the panels of the walls, or between the panes of the display panel is absorbed, in the interest of better refrigeration as well as a satisfactory display of goods within the refrigerator. Another object is the provision of a structure especially adapted for the expulsion of moist air from and the admission of dry air, or any suitable gas, to the space between the panes which are set into the wall of the refrigerator to form a display panel. The invention is illustrated in the accompanying drawings and will be hereinafter fully set forth and defined.

In the drawings:—

Fig. 1 is a front elevation of the upper portion of a display refrigerator embodying the invention;

Fig. 2 is an end elevation of the same;

Fig. 3 is an enlarged section on the line 3—3 of Fig. 1;

Fig. 4 is a section similar to Fig. 3 illustrating a moisture-absorbing arrangement;

Fig. 5 is an enlarged longitudinal section of the upper portion of the device shown in Fig. 4;

Fig. 6 is a section on the line 6—6 of Fig. 5;

Fig. 7 is a sectional perspective view of a refrigerator construction on a larger scale.

The refrigerator, indicated at 1, may be of any known or approved construction having walls constructed of hollow panels as indicated in Fig. 7, or having glazed panels for the display of foods, which panels may be fixed as indicated at 2 in Figs. 1, 2, 3 and 4, or may be part of a door as indicated at 3 in Fig. 7. The panels comprise a sash or frame 4 into which glass panes 5 are set to establish a dead-air chamber 6 between the panes, and it may be here noted that usu-

ally only a single chamber is formed but three or more panes may be employed and two or more chambers thereby formed as shown in Fig. 7.

The purpose of having a plurality of panes forming one or more chambers, is to provide the insulation which must be present in all of the walls and which would not be supplied by a single pane.

In the walls or sides of the refrigerator where no display features are involved, veneer or the like may be used in lieu of the glass panes, to form a suitable insulating space or panel. This wall structure may be of any conventional and well known type, regardless of material, examples being the ends and rear of the case in Figs. 1 and 2, and the walls shown in section in Fig. 7.

It will be noted that the walls illustrated comprise a series of cells or chambers, and obviously the cells or chambers may be reduced in size and increased in number.

Atmospheric air always contains moisture which, getting into the air cells of the insulation or into the hollow panels renders the insulation (whether it be a panel, or a cellular structure) less efficient. Again, when the air is not circulating, this moisture condenses upon the surfaces of the glass panes, so as to obscure the view through them and cause great annoyance to storekeepers dealing in perishable food products. Especially is this true when, as in refrigerators, there is a difference in temperatures on opposite sides of the glass. To meet and overcome this condition, the present invention provides tubes or passages 7, of any suitable material, which are fitted snugly through the frame of the wall, door or panel and open at their inner ends into the space 6 and at their outer ends into the atmosphere. These passages may, of course, be formed by drilling without necessitating the use of tubes fitted in the panel.

After the refrigerator is finished, the outer

- end of one tube 7 is connected to an air pump and a gas or dehydrated air is forced into the chamber 6 so as to substantially fill the same and drive out the atmospheric air 5 through the other tube. After all the moist or atmospheric air has been driven out, the outer ends of both tubes are closed by stoppers 8 of non-porous material which will fit tightly in the tubes and exclude moisture, the 10 stoppers, like the tubes, being of any suitable material, for example, rubber, to effect the requisite close fit in the tube and remain unaffected by any moisture in the surrounding atmospheric air, it being understood that 15 suitable luting is provided around the ends of the tubes and the edges of the panels.
- While in the form of the invention shown in the drawings, two tubes are used, it is obvious that one tube only could be used, the 20 space between the panes being partially exhausted, and the vacuum thus formed filled with gas or dehumidified air, which would naturally rush in and fill the space without creating a pressure.
- 25 Glass panes may be broken in use or, for some other reason, moisture may find its way into the dead-air chamber or into the insulation after the refrigerator has left the factory, and to meet this condition a moisture-absorbent agent is provided, and placed 30 in communication with the interior of the chamber either by insertion into a tube or passage or by location in such a position as to communicate through the tube or passage 35 with the chamber. In Fig. 4, this agent is shown as a wick 9, of some material having high moisture-absorbing qualities, which is held in shape by a wire-mesh casing 10 inser-
- 40 tible through the tube 7. At points between its ends, spacing collars 11 are mounted on the casing 10, and at its upper or outer end it is attached to a ferrule or thimble 12 which may be connected to the stopper 8 by a link or short chain 13. In Figs. 5 and 6, 45 a cartridge 14 of calcium chloride, lime or other substance having the property of absorbing moisture from the atmosphere is substituted for the wick 9, the device, otherwise, being the same as that shown in Fig. 4. In 50 Fig. 7, the spacers 15 between the glass panes 5 are of soft wood or of fibre, which has been baked and thoroughly dried and then wrapped in paraffine paper or other moisture-proof covering until it is built into the 55 refrigerator, so that these spacers form moisture-absorbing elements for the dead-air spaces. It is obvious that the wicking, cartridges, or other removable moisture-absorb- 60 ing agent may be renewed as often as necessary, and different types of agents may be used in combination with each other. For instance, it may be desirable to provide spacers of absorbent material in the first instance and either at that time or subsequent thereto 65 it may be found desirable to insert a car-

tridge. This arrangement is shown in Fig. 7. It is intended that these agents be supplied by the manufacturer of the refrigerator. The stoppers 8, casing 10, ferrule 12 and chain 13 provide a means to replace or renew the moisture absorbing agent when necessary.

To provide access to the panels for inserting or renewing the moisture-absorbing agent, the top 16 of the refrigerator may be 75 removable or may be so spaced or shaped as to permit the operator to reach under it.

If desired, the tube or tubes may be inserted at either the end stiles or lower rail of the case instead of in the top rail as shown. 80 In fact it may be advisable in some forms of cases utilizing this invention to insert a tube in the member around the air space in the rear sliding doors, which are naturally of insulating construction.

Obviously the wicking, cartridge, dried spacer or other suitable moisture absorbent agent may be extended throughout the height or length of the enclosed space, or may be located around any portion of the 90 outside edges of the glass, within the chamber, or without the chamber, but in communication therewith, as desired, the only fundamental requirement being that of moisture absorption capacity.

95 From the foregoing description, taken in connection with the accompanying drawings, it will be seen that I have provided a simple construction which may be readily included in any refrigerator without any 100 considerable expense, and that by the practice of my invention the dead-air space of the refrigerator will be freed of moisture, whether that space be enclosed between glass panes, or in a hollow wall panel formed of other material than glass and dulling of the glass-panels in a display refrigerator by condensation will be avoided.

105 In short, it is substantially impossible to prevent permeation of any wood or kindred material from which refrigerators are usually built, by water vapor which is deleterious to refrigeration, and acts to break down the insulating effect of the refrigerator walls which depend upon a dry cellular formation 110 or a hollow, dry tight air space for this effect, and which obscures the vision, as well of an insulating glass panel. Hence this invention is decidedly advantageous in that 115 it provides initiation and maintenance of a dry condition in the walls and panels or for that matter in any insulated portion of the refrigerator.

120 Having thus described my invention, what I claim as new and desire to secure by Letters Patent of the United States, is:—

125 1. In a refrigerator having a wall portion formed by panes of glass, spacers for said panes, fluid chambers formed between the panes, means in said spacers affording 130

- communication with said chambers, and means coacting with said first means to dry the fluid within said chamber.
2. A wall structure for refrigerators embodying an insulating chamber, open-ended tubes projected through a wall of the structure into the chamber whereby a substantially dry fluid may be driven into the chamber and atmospheric air driven therefrom, means to maintain said fluid in a dry condition while in the chamber, and means for closing the outer ends of the tubes.
3. A wall structure for refrigerators embodying a fluid containing insulating chamber, having passages through the wall of said chamber and effective to form an inlet to, and an outlet from the chamber, closures for the passages and a moisture-absorbing agent removably mounted in one of the passages.
4. A structure including a frame, panes in the frame defining a fluid containing insulating chamber, closed to the atmosphere and spacers of absorbent material between the panes and protected from the atmosphere.
5. A wall structure for refrigerators embodying a fluid containing insulating chamber closed to the atmosphere, a passage in a wall of said chamber, a moisture-absorbing body, means to support said body from said passage and in communication with the chamber to maintain the fluid in a dry condition and thereby increase the insulating effect of said chamber, and a foraminous casing for said body.
6. A structure embodying a fluid containing chamber, a passage extending through the wall of said chamber, a closure for said passage, a ferrule connected with said closure, a foraminous casing secured to the ferrule and extending through the passage, and a moisture-absorbing body in said casing.
7. A refrigerator having a wall portion formed by spaced panes of glass, a chamber between said panes adapted to contain fluid, means between said panes establishing communication between the interior and exterior of said chamber and means comprising a drying agent and a seal coacting with said first means to break communication with the atmosphere.
8. A panel structure for refrigerators embodying a fluid containing insulating chamber, closed to the atmosphere, a passage in a wall of said chamber a moisture-absorbing agent, means to support said agent from said passage and in communication with said chamber to maintain the fluid in a dry condition and thereby increase the insulating effect of said chamber, and means to seal said agent in the chamber from external influences.
9. A structure embodying a dead-air chamber, a passage extending through a wall of said chamber, and in communication with the chamber, and a moisture-absorbing ma-
- terial in the passage, and means to protect said material from the atmosphere.
10. A structure embodying a dead-air chamber, a passage extending through a wall of said chamber, a moisture-absorbing material in said passage, and means for renewing the moisture absorbing material.
11. A structure embodying a dead-air chamber, having passages through the wall of said chamber, a moisture-absorbing material in one of said passages and a replaceable casing for said moisture-absorbing material.
12. In a refrigerator having insulating wall portions formed of glass lights, a chamber defined by said lights and closed to the atmosphere and containing a dehydrated gas, a passage extending between said lights, and an absorbing agent, means to support said agent from said passage and within said chamber to maintain the gas in a dry condition and thereby increase the insulating effect of the chamber.
13. A structure including a frame, panes of glass in said frame defining a dead-air chamber therebetween, spacers of absorbent material between the panes and an absorbent material inserted in said chamber.
14. A structure embodying a dead-air chamber, a moisture-absorbing body hung in the wall of said chamber, and means for renewing the moisture absorbing body.
15. A refrigerator wall structure comprising a panel embodying a fluid containing, insulating chamber closed to the atmosphere, a passage in a wall of said chamber, a moisture absorbing agent, and means to support said agent from said passage in communication with said chamber and protected from the atmosphere.
16. A refrigerator having a spaced wall portion forming an insulated cell, a passage extending through a wall of said cell, and a moisture absorbing agent supported in said passage and in communication with the cell to maintain the interior of the cell in a dry condition and thereby increase the insulating effect of the cell, and means for replacing said agent.
17. A refrigerator having a spaced wall portion forming an insulating cell, a passage extending through a wall of said cell, a moisture absorbing agent supported in said passage and in communication with the cell to maintain the interior of the cell in a dry condition and thereby increase the insulating effect of the cell, and means in said passage to protect the agent from the atmosphere.
18. In a refrigerator, a wall, said wall including a transparent panel comprising a plurality of spaced plates, said wall adjacent said panel having therein a pocket, the frame of said panel having a passage therethrough from said pocket into the space between said transparent plates, and said wall also hav-

- ing an opening therein from a side thereof into said pocket, a closure for said opening, and a receptacle for a drying agent positioned in said pocket and removable therefrom through said opening. 5
19. A structure embodying a fluid containing chamber, a passage extending through the wall of said chamber, a closure for said passage, a perforated casing, means to support said casing from said passage with the casing extending to said chamber, and a moisture absorbing body in said casing and communicating with said chamber through the perforations of the casing. 10
20. The combination with a heat insulating panel for a refrigerator having a refrigerating space, of a substantially air tight chamber located within the panel adjacent said refrigerating space, and provided with an opening and a moisture absorbing element mounted in said opening. 15
21. The combination with a heat insulating panel for a refrigerator, having a refrigerating space, of a substantially air tight chamber located within the panel adjacent said refrigerating space, and provided with an aperture at one side of said chamber, and with a second aperture at the other side of said chamber and hygroscopic means within 25 said chamber. 30
22. In a refrigerator having a refrigerating space, and means for cooling same, a panel embodying a dead air insulating chamber adjacent said space, a moisture absorbing body supported by a wall of said chamber, and means for renewing the moisture absorbing body. 35
23. The combination in a refrigerator having a cooling space, of a heat insulating panel adjacent said space, a substantially air tight chamber located within said panel and sealed from the interior of the cooling space, of means for supplying dry fluid to said chamber, including an inlet and outlet for the chamber, and means to maintain said fluid in a substantially dry condition while in the chamber. 40
24. A wall structure for refrigerators embodying an insulating chamber, inlet and outlet passages extending through a wall of the structure into the chamber, whereby a substantially dry fluid may be driven into the chamber and atmospheric air driven therefrom, means to maintain said fluid in a substantially dry condition while in the chamber, and means for sealing the outer ends of the passages. 45
25. The combination with a heat insulating panel for refrigerators, of a substantially air tight chamber located within the panel and provided with means to establish communication between the interior of the chamber and the exterior of the panel, whereby a substantially dry fluid may be driven into the chamber and atmospheric air driven there- 50 55 60 65 70 75 80 85 90 95 100 105 110 115 120 125 130
